UNITED STATES PATENT OFFICE.

EDUARD PIELOCK, OF BERLIN, GERMANY.

STEAM-GENERATOR.

1,082,136.

Specification of Letters Patent.

Patented Dec. 23, 1913.

Application filed January 23, 1912. Serial No. 672,934.

To all whom it may concern:

Be it known that I, EDUARD PIELOCK, a subject of the Emperor of Germany, and resident at Landshuterstrasse 14, Berlin, W., 5 Germany, have invented a certain new and useful Steam-Generator, of which the following is a specification.

This invention relates to steam generators and to a method of completely utilizing the 10 heating gases and it is the object of the present invention to provide improved means whereby to achieve the said method in a more efficient manner.

It is a well known fact that the utilization 15 of the heating gases in most steam generator constructions is unsatisfactory, especially so when the heating surfaces are subjected to very heavy working conditions. Locomotive boilers, which generally work 20 at 40 kg. steam generation per sq. m. heating surface per hour, have on an average an efficiency of 55%. With low working conditions the efficiency increases but the steam generation becomes mostly insufficient for 25 the actual requirements. In many instances especially for ships' boilers, the allotted space is an important factor because the smallest location must serve for the most efficient steam generating plant. Conversely 30 the working conditions of the heating surfaces must be improved as compared with existing arrangements, and a better utilization of the heat from the furnace gases must be provided for.

To obtain a more perfect utilization and 35 combustion of the furnace gases, according to this invention, means are adopted for constantly mixing these gases along their whole path as far as is possible and particularly in higher temperatures. By proceeding in this manner, the cooler gases are 40 mixed with hotter gases and therefore have a better effect in giving up heat, while, moreover, incompletely oxidized gases or de- 45 oxidized gases become more completely oxidized or re-oxidized as the case may be.

An effective mixture can, according to this 50 invention, be attained by causing the gases to become alternately compressed and then forcibly expanded. The compression is best 55 attained by forcing same through a minimum opening or restricted portion of very short length so as to keep the resistance as low as possible. The forcible expansion can be attained, for example, by placing tubes in the fire tube at the rear of each restricted

portion. For mixing the gases, they can also be repeatedly diverted from their straight path. In steam generators, which have a chamber between the fire box and the multitubular boiler, a deflecting wall 60 may be provided so as to facilitate consumption of smoke and separate solids from the fire gases. For generators having a vertical fire box, the latter may advantageously be 65 surrounded with steeply inclined heating tubes to receive the gases previously deflect- ed from their straight path in the fire box. The gases issuing from the heating tubes are advantageously led into a chamber to 70 intermix and thence flow through a further series of tubes in another direction.

Steam generators, having a horizontal fire-box, should have its flue-tube tapering down toward the rear but always in combination with the aforesaid features. 75

Various forms of the improved steam generators are shown in the accompanying drawings, in which:

Figure 1 is a longitudinal section of a locomotive boiler, Fig. 2 is a vertical section of an upright steam generator. Fig. 3 is a vertical section of a modified generator, Fig. 4 is a longitudinal section of a horizontal generator, Figs. 5, 6, 7 and 9 are longitudinal sections of variously obstructed flue tubes, Fig. 8 is a cross-section of the tube shown in Fig. 7, Fig. 10 is a cross-section of the tube shown in Fig. 9. 80

Referring to Fig. 1, the locomotive boiler 90 comprises an upright fire-box *a* and a horizontal multi-tubular boiler *b* with an intervening chamber *c*. The gases from the fire grate *d* are compressed through a restricted portion *e* in the interior of the firebox and 95 are then divided up by superposed tubes *f* and expanded in the upper space *G* to be again compressed in the restricted passage *h* leading into the comparatively large chamber *c* in which the wall *i* causes a two-fold change of direction of flow and a renewed expansion of the gases before being divided 100 into separate currents by the tubes *k*. The wall *i* is made of fire-bricks which become incandescent and insure the consumption of smoke and the separation of solids from the gases, said solids collecting in the lower space *l*, so that the tubes *k* are kept clean and sparks from the chimney are avoided. 105

In the upright generator, shown in Fig. 2, 110 the gases from the furnace *m* pass through restricted portions up against the wall *n*

whence they are deflected into inclined downwardly leading flame tubes and are again deflected before collecting in the smoke box *o* for heating the boiler walls. 5 With this construction, a comparatively small base of furnace enables the best effects of heating to be insured. A similar system is adopted with the construction shown in Fig. 3, but the gases are further directed 10 from the chamber *x* into a series of vertical flame tubes *w*. The gases in the chamber *x* mix again and are once more deflected and this without coming into useless contact with external cooling surfaces, such as is the case 15 in Fig. 2 during their passage along the chamber *o*.

The horizontal generator, shown in Fig. 4, is equally arranged for carrying the aforesaid method into effect. The smooth or 20 corrugated furnace tube is cylindrical and of suitable diameter for the required grate. As the combustion gases normally tend to pass straight into the chimney, and it is therefore necessary to force the gases into 25 contact with the heating surfaces of the generator in order to utilize all their heat. This cannot be effected in smooth cylindrical flue tubes, and the gases take about the direction shown by the line *p* so that over a large part 30 of the lower portion of the flue tube no direct heat is given off. Flue tubes of this description have been made with stepped portions, but even these do not conduce to the complete utilization of the heat from the 35 gases. For this purpose, the gases must be alternately compressed and split up, and this is carried out in tubes constructed as follows: The tube *q*, containing the grate and fire bridge *r*, has a restriction at the rear of 40 the bridge so that the fire gases become split by the tube *s* and compressed by the restriction *t*, then again split by the tube *s*¹ then compressed by the restriction *t*¹, split by *s*², compressed by the restriction *t*², split by *s*³, 45 compressed by *t*³ and so forth throughout the length of the flue tube. The cross-sections of *t*, *t*¹, *t*², *t*³ and so forth as well as the flue tube are of gradually reduced diameter to correspond with the gradual cooling of 50 the gases. For this purpose the tube is made of graduated sections *v*, *v*¹, *v*², *v*³ and so on. The method applied to the firebox as shown

in the Figs. 1-4, can also be carried into effect in the flame tubes of multi-tubular boilers as shown in Figs. 5-10. These tubes 55 are fitted with rings *a* which retain intermediate longitudinal bars *b* of stepwise or wavy form. The bars *b* may be interlaced as shown in Fig. 10 so as to more effectually split up the gases as well as compress same 60 repeatedly altering their direction.

I claim:

1. In a boiler, a fire box provided with side walls and a top having a centrally disposed opening, a flue extending from said opening and having an enlarged portion located above the opening, the upper end of said flue being constricted, a chamber located above the upper end of said flue, a water chamber surrounding said fire box, 70 flue and chamber, said water chamber being provided with an outer wall and the walls of the fire box, flue and first mentioned chamber forming the inner wall of the water chamber, downwardly directed fire tubes 75 leading from the first mentioned chamber through the water chamber, and a water tube extending transversely through said flue.

2. In a boiler, a fire box provided with 80 side walls and a top having a centrally disposed opening, a flue extending from said opening and having an enlarged portion located above the opening, the upper end of said flue being constricted, a chamber located 85 above the upper end of said flue, a water chamber surrounding said fire box, flue and chamber, said water chamber being provided with an outer wall and the walls of the fire box, flue and first mentioned chamber forming 90 the inner wall of the water chamber, downwardly directed tubes leading from the first mentioned chamber through the water chamber, a water tube extending transversely through said flue, a mixing chamber 95 at the lower ends of said fire tubes, and vertical fire tubes leading upward through said water chamber from said mixing chamber.

In testimony whereof I have hereunto set my hand in presence of two witnesses.

EDUARD PIELOCK.
